US0D1029679S

(12) **United States Design Patent** (10) **Patent No.:** **US D1,029,679 S**
(45) **Date of Patent:** **** Jun. 4, 2024**

(54) **PLANT SUPPORT**

(71) Applicant: **Yongzong Li**, Guangdong (CN)

(72) Inventor: **Yongzong Li**, Guangdong (CN)

(**) Term: **15 Years**

(21) Appl. No.: **29/905,608**

(22) Filed: **Oct. 23, 2023**

(51) **LOC (14) Cl.** **11-02**

(52) **U.S. Cl.**

USPC **D11/143**

(58) **Field of Classification Search**

USPC D6/403, 513, 558; D11/143, 148, 152,
D11/153, 154

CPC A01G 9/12; A01G 13/0243; A01G 9/022;
A47G 7/044

See application file for complete search history.

(57) **CLAIM**

The ornamental design for a plant support, as shown and described.

DESCRIPTION

FIG. 1 is a front and top perspective view of a plant support, showing my new design;

FIG. 2 is a rear and bottom perspective view thereof;

FIG. 3 is a front elevational view thereof;

FIG. 4 is a rear elevational view thereof;

FIG. 5 is a left elevational view thereof;

FIG. 6 is a right elevational view thereof;

FIG. 7 is a top plan view thereof; and,

FIG. 8 is a bottom plan view thereof.

The broken lines in the figures depict portions of the plant support that form no part of the claimed design.

1 Claim, 8 Drawing Sheets
